(57) **CLAIM**

The ornamental design for a hummingbird nectar feeder, as shown and described.

DESCRIPTION

FIG. 1 is a front perspective view of a hummingbird nectar feeder embodying my new design.

FIG. 2 is a front elevational view thereof.

FIG. 3 is a back view thereof.

FIG. 4 top view thereof; and,

FIG. 5 is a bottom view thereof.

The portions shown in broken line are not claimed.
